UNITED STATES PATENT OFFICE.

BERNARD ARTHUR BEHREND, OF NORWOOD, OHIO, ASSIGNOR, BY DIRECT AND MESNE ASSIGNMENTS, TO THE BULLOCK ELECTRIC MANUFACTURING COMPANY, A CORPORATION OF OHIO, AND ALLIS-CHALMERS COMPANY, A CORPORATION OF NEW JERSEY.

DYNAMO-ELECTRIC MACHINE.

964,742.

Specification of Letters Patent.

Patented July 19, 1910.

Application filed December 28, 1904. Serial No. 238,174.

To all whom it may concern:

Be it known that I, BERNARD A. BEHREND, citizen of the United States, residing at Norwood, in the county of Hamilton and State 5 of Ohio, have invented certain new and useful Improvements in Dynamo-Electric Machines, of which the following is a full, clear, and exact specification.

My invention relates to improvements in 10 dynamo-electric machines with especial reference to machines of the double commutator type.

In operating double commutator generators, considerable difficulty has been experienced due to an unbalancing of the load on 15 the machine; that is, due to an unsymmetrical distribution of the current between the commutators of the generator armature. This is especially true of multipolar machines 20 employing a large number of carbon brushes or collectors. In such machines there is a tendency for certain of the brushes on the machine, or all of the brushes on a single commutator, to "grab" the load, as it 25 is called. This so called "grabbing" of the load takes place as follows:—As the result of some local disturbance, such for instance as dirt or dust between the commutator and brushes, or a brush of peculiar composition, 30 or due to a relatively low resistance feeder connection, or for some other reason, the path for the current from the armature winding through certain of the brushes is at first of slightly lower resistance than is 35 the path through certain other brushes. This condition causes the first mentioned brushes to at first take a little more current than is taken by the other brushes. As is well known, a carbon brush has less resistance 40 when hot than when cool, and as the resistance of said brush drops very rapidly as the current density and consequently the heat increases, it will be seen that the first mentioned brushes offer less and less resistance 45 to the passage of current than do the other brushes. As a result said first-mentioned brushes heat up quite rapidly, and as they heat up, they take more and more of the current until, as sometimes happens, the 50 brushes on a single commutator are carrying the entire current of the machine, leaving the other commutator and brushes practically currentless. Under these conditions, the commutator, brushes, and brush holders

on one side of the machine are greatly over- 55 loaded, since they are designed to carry one-half of the current of the machine and not the whole current. This unbalanced condition is productive of considerable sparking and it often happens that the brushes, brush 60 holders, and commutators are entirely destroyed as the result of the sparking and excessive heating. In large machines which are subject to heavy and sudden overloads, it sometimes happens that the commutator 65 will flash over; that is, the current will jump from brush to brush along the surface of the commutator severely damaging the latter and often ruining it.

The objects of my invention are to overcome the difficulties above enumerated, to prevent burning of the brushes and brush 70 holders, to prevent flashing on the commutator, and to simplify the connections to the brushes or collectors of such a machine. 75

In carrying out my invention I provide for each commutator of a multi-commutator dynamo-electric machine positive and negative collecting devices, the positive collecting devices for one commutator having a 80 resistance materially greater than the negative collecting devices for the same commutator, and the positive collecting devices for the second commutator having a resistance materially less than the negative collecting devices for the second commutator, 85 so that one commutator carries the bulk of the positive current and the second commutator carries the bulk of the negative current. The above result may be accomplished 90 by employing positive and negative brushes of materially different resistances, or by employing between the positive and negative brushes of each commutator and the positive and negative mains respectively, leads or 95 conductors of materially different resistances. Preferably, the positive collecting devices for one commutator have substantially the same resistance as the negative collecting devices for the second commutator, 100 and the negative collecting devices for the first commutator have a resistance substantially the same as the positive collecting devices for the second commutator but materially different from the resistance of the 105 positive collecting devices for the first commutator.

The invention further comprises other

combinations of parts of the system, which will be hereinafter described and more specifically pointed out in the appended claims.

In the accompanying drawings, Figures 1 and 2 are side elevations of the armatures of bipolar double commutator machines with different brush connections; Figs. 3 and 4 are developments of the commutators of multipolar double commutator machines with different brush connections; and Figs. 5 and 6 are developments of the commutators of two multipolar double-commutator machines showing the brushes connected in a slightly different manner.

In Figs. 1 and 2 I have illustrated the development of a double commutator bi-polar generator from a condition of balanced, unstable equilibrium to a condition of artificially unbalanced stable equilibrium. In Fig. 1 the positive brushes are indicated by 21^a and 21^b, resting on commutators 19 and 20 respectively and connected together by lead 23, which in turn is connected to the positive main 24. The negative brushes 22^a and 22^b rest on commutators 19 and 20 respectively and are connected together by lead 25 which is connected to negative main 26. This machine is supposed to be balanced, the brushes, including their leads being all of the same resistance and current carrying capacity. The commutators and brushes resting thereupon are each designed to carry one-half the current of the machine. Now, suppose for some reason or other, say for instance, dirt or dust between the brushes 21^a and 22^a and commutator 19, the circuit through this brush becomes of slightly higher resistance, either at starting or while running under load, than the remaining brushes, then there will be a tendency for more current to flow through the brushes on commutator 20. If this unbalanced condition exists for a short time the commutator 20 and its contacting brushes "grab" the load of the machine in the following manner; as the current density in the carbon brushes 21^b and 22^b increases, the ohmic resistances of these brushes will drop very rapidly, the current density and consequent heating will increase, and the resistances will drop further until such a point is reached that the commutator 20 is carrying all, or practically all, the current of the generator. While this is taking place it will be seen that as commutator 19 is being deprived of current, the brushes 21^a and 22^a, having the current density therein reduced and thus becoming cooler offer more and more resistance to the passage of the current from commutator 19, thereby assisting the commutator 20 in "grabbing the load". The brushes 21^b and 22^b and commutator 20 are now operating on a very heavy current overload and practically double the current for which they were designed. The

result is obvious; the commutator 20 is pitted by sparking and ultimately destroyed, the brushes and brush holders burn out, and the operation of the machine is anything but satisfactory. To obviate these difficulties, and render the machine perfectly stable, I propose to unbalance the machine artificially and divide the current between the commutator brushes in such a manner that it is impossible for any one commutator to "grab" the entire load. This I accomplish as shown in Fig. 2 by making some of the brushes, viz. brushes and leads 21^a and 22^b on each commutator of relatively low resistance and large current-carrying capacity, and the remaining brushes of relatively high resistance and small current-carrying capacity. The brushes 21^a and 21^b are connected to the positive main 24 and the brushes 22^a and 22^b are connected to the negative main 26. This forces the major part of the current of the machine to flow from the armature winding through the commutator 19 and brush 21^a to the positive main and return through the negative main 26, brush 22^b and commutator 20, to the armature winding. The remainder of the current flows through the commutator 20 and brush 21^b, returning through brush 22^a and commutator 19.

In Figs. 3 and 4 I have shown the development of the commutators, and a diagrammatic representation of the brushes and connections thereto, of a multipolar generator of the double commutator type. Fig. 3 shows a balanced unstable condition with the brushes and leads 21^a, 21^b, 22^a and 22^b of equal resistance and connected to the distributing mains 24 and 26 in the manner shown. Fig. 4 shows a stable, artificially unbalanced condition with the brushes and leads 21^a and 22^b of low resistance and the brushes and leads 21^b and 22^a of high resistance, all connected to the same system of distribution.

Figs. 5 and 6 illustrate in development the commutators of machines similar to those illustrated in Figs. 3 and 4, but with the brushes connected in a slightly different manner, Fig. 5 showing a balanced unstable operating condition and Fig. 6 showing an artificially unbalanced, but stable condition. In Fig. 5 the brushes and leads are all of equal resistance. The positive brushes 21^a and 21^b are connected to separate leads 24^a and 24^b on opposite sides of the machine instead of being connected across the machine to the same lead as in Figs. 3 and 4. The brushes 22^a and 22^b are connected to separate leads 26^a and 26^b in a similar manner. These leads are connected to the distributing mains 24 and 26 as shown.

To unbalance this system artificially to produce a stable operating condition, I make the brushes 22^a and 21^b and the leads 26^a and 24^b of unequal resistance.

and 24^b of low resistance and the brushes 21^a and 22^b and leads 24^a and 26^b of high resistance, so that the first mentioned brushes and leads will carry the bulk of the current 5 of the generator. The leads and connections of different resistances assist the brushes of different resistances in maintaining a stable operating condition.

It will be readily seen from the above 10 statements that to artificially unbalance the current distribution between the positive and negative brushes of each commutator so as to maintain stable operation, it is necessary that the total resistances of the current 15 conducting or collecting devices connecting each main to the two commutators be different, and that leads or connections of different resistances may assist brushes of different resistances to maintain stable operation. 20 or if the brushes are of the same resistance leads of different resistances may be employed, and if the leads are of the same resistance brushes of different resistances may alone act to maintain stable operation. 25 It will be understood that by the expression "collecting devices" I mean to include either brushes or the conductors which connect the brushes to the mains.

Although I have illustrated my invention 30 as applied to a double commutator machine, having commutators on opposite sides thereof, it will be readily understood that said invention is equally applicable to a machine having more than two commutators, 35 and also to machines having more than one commutator at one end thereof. Therefore I aim in the appended claims to cover all modifications of the mechanism herein shown and described which do not involve a 40 departure from its spirit and scope.

Having thus described my invention, what I claim as new and desire to secure by Letters Patent is:

1. In a multi-commutator dynamo-electric machine, positive and negative collecting devices for each commutator, the positive collecting devices for one commutator having a resistance materially greater than the negative collecting devices for the same 45 commutator, and the positive collecting devices for the second commutator having a resistance materially less than the negative collecting devices for the second commutator.

50 2. A double commutator dynamo-electric machine having means for artificially un-

balancing the load on each commutator of the machine in a predetermined manner, said means comprising a brush or brushes of high resistance and a brush or brushes of low resistance on each commutator, the high resistance brush or brushes on one commutator and the low resistance brush or brushes on the other commutator being connected to one side of a system of distribution, and the remaining brushes being connected to the other side of said system of distribution in such a manner that one commutator carries the bulk of the positive current and the other commutator carries the bulk of the negative 70 current.

3. In a double commutator dynamo-electric machine, high resistance brushes and low resistance brushes on each commutator, leads of high resistance connected to the 75 high resistance brushes, leads of low resistance connected to the low resistance brushes, and connections between the high resistance leads from the brushes of one commutator and the low resistance leads from the brushes 80 on the other commutator.

4. In a multi-commutator dynamo-electric machine, positive and negative collecting devices for each commutator, the positive collecting devices for one commutator 85 having substantially the same resistance as the negative collecting devices for the second commutator, and the negative collecting devices for the first commutator having substantially the same resistance as the positive 90 collecting devices for the second commutator, but having a materially different resistance than the positive collecting devices for the first commutator.

5. In a dynamo-electric machine, an armature, two commutators connected to the winding of said armature, the positive brushes on one commutator having substantially the same resistance as the negative brushes on the other commutator, and the 100 negative brushes on the first commutator having substantially the same resistance as the positive brushes on the second commutator but having a greater resistance than the positive brushes on the first commutator. 105

In testimony whereof I affix my signature, in the presence of two witnesses.
